PROPELLER FOR SUBMERGING AND STEERING SUBAQUEOUS AND FLOATING VESSELS

Application filed May 22, 1930, Serial No. 454,764, and in Italy May 28, 1929.

This invention relates to an oscillating propeller or fin for submerging and steering subaqueous and floating vessels.

Practice has shown that the use of such propellers or fins, oscillatable through a sector and formed of a flexible plate of decreasing thickness, and the action of which is based on the reaction of elastic material, has not fully realized the purpose aimed at, owing to the structural difficulties involved in making the blades have a decreasing thickness from their point of attachment to the propeller shaft towards their tip.

The object of the present invention is to remove this difficulty completely.

The invention consists in an oscillating propeller or fin for submerging and steering submarine and surface vessels, comprising a plate and flexible arms securing this plate to the oscillatable axis of the fin.

The invention further consists in an oscillating propeller or fin for steering submarine and surface vessels, comprising a plate and flexible arms having a flexibility increasing from root to tip connecting this plate to the oscillatable shaft carrying the fin.

According to a further feature of the invention, these flexible arms have a constant thickness and a gradually decreasing width from root to tip.

The invention will now be described with reference to the accompanying drawings, in which:

Figure 1 is a front view of the propeller or fin.

Figure 2 is a side view.

Figure 3 shows a diagram of movement.

Figure 4 shows a submersible vessel fitted with the improved propellers according to the invention.

In carrying the invention into effect in the form illustrated, the new propeller or fin comprises a rigid plate *a* with one or more flexible arms *b* fixed to it at *c* and preferably, but not necessarily, a base plate *d* for connecting and fixing the arms *b*. The plate *a* may be integral with the arms *b* and its object is to produce the flexion of the arms *b* owing to the resistance met with during the oscillation through angles within 90° (see Figure 2).

The arms *b* which always tend to return to a position of rest, impart a thrust (due to molecular resistance) to the axis or attachment point (propeller shaft *m*) proportional to the elasticity and the number of flexions per minute.

This type of propeller may be employed for overcoming the upward thrust due to buoyancy in submarine craft, and for steering them both at the surface and when submerged, any desired evolution being effected. It may also be used for raising the vessel to the surface when the latter, owing to a leak, becomes heavier than the displaced fluid.

Practice has shown that:

1. The propellers or fins according to the invention, when fitted to the sides of the vessel fore and aft, are capable of overcoming a considerable buoyancy, thereby permitting the vessel to be submerged immediately with parallel displacements, without resorting to flooding the tanks.

2. By regulating the movement of the propellers until equilibrium is reached between the down thrust of the propellers and the buoyancy of the vessel, the latter can be held in perfect equilibrium within the water (between the surface and the bottom) or it may perform all evolutions as if it were floating on the surface.

3. Evolutions may be effected around the vertical axis *o* of the vessel by operating the said propellers in a horizontal sector, those at the bow being operated in the opposite direction to those at the stern.

4. Parallel horizontal movements of the vessel may be effected by operating both propellers in horizontal sectors, but in the same direction, both fore and aft.

5. The vessel may be brought to the surface by stopping the driving apparatus. The buoyancy of the apparatus vessel may be employed for raising it to the surface, by stopping the driving apparatus.

6. When the vessel is heavier than the displaced fluid it may be returned to the surface by operating the propellers with their tip directed downwards, i. e. with the axis of movement upwards with regard to the propeller.

Figure 3 shows the four sectors of movement in which the propellers may be operated for steering and submerging the vessel; namely, the sector h for submersion, the sectors h' , h'' for combined horizontal movements, as above described, and the sector h''' for emersion in the case when the vessel is weighted owing to a leak, or for rapid emersion by adding the dynamic thrust of the propellers to the upward thrust of the buoyancy.

Having now particularly described and ascertained the nature of my said invention and in what manner the same is to be performed I declare that what I claim is:

15. 1. In propellers as described, flexible arms with parallel thicknesses, fixed at the top to the rigid plate or integral therewith, and fixed at the bottom to the propeller shaft, their shape being broad at the base and decreasing in width towards the attachment point to the rigid resistance plate.
20. 2. An oscillating propeller or fin for submerging and steering submarine and surface vessels, comprising a plate and flexible arms having a flexibility increasing from root to tip connecting this plate to the oscillatable shaft carrying the fin.
25. 3. An oscillating propeller or fin for submerging and steering submarine and surface vessels, comprising a rigid plate and flexible arms having a flexibility increasing from root to tip connecting this plate to the oscillatable shaft carrying the fin.
30. 4. An oscillating propeller or fin for submerging and steering submarine and surface vessels comprising a plate and flexible arms having a constant thickness and a gradually decreasing width from root to tip connecting this plate to the oscillatable shaft carrying the fin.
35. 5. An oscillating propeller or fin for submerging or/and steering surface and submarine vessels, comprising a plate and flexible arms forming the sole connection between this plate and the oscillatable axis of the fin and whereby the oscillating movement of the axis is transmitted to the plate.

In testimony whereof I have signed my name to this specification.

UGO ANTONI.
